UNITED STATES PATENT OFFICE.

CHARLES H. SCHOPBACH, OF AURORA, ILLINOIS, ASSIGNOR TO INTERNATIONAL CORSET COMPANY, OF AURORA, ILLINOIS, A CORPORATION OF ILLINOIS.

COMBINED CORSET AND BRASSIÈRE.

Application filed February 8, 1923. Serial No. 617,685.

To all whom it may concern:

Be it known that I, CHARLES H. SCHOPBACH, a citizen of the United States, residing at Aurora, in the county of Cook and 5 State of Illinois, have invented certain new and useful Improvements in Combined Corsets and Brassières, of which the following is a specification, reference being had to the accompanying drawings and to the reference 10 characters marked thereon, which form a part of this specification.

This invention relates to wearing apparel, and has special reference to corsets and brassières combined in one garment.

15 The primary object of the present invention is an improved arrangement and construction of parts, whereby the function of a corset and of a brassière may be utilized in one garment; whereby the back of the 20 wearer will be substantially covered by a unitary section of the garment, the abdominal portion of the body will be covered by front-fastening, corset-like parts which are adjustably yielding and also supporting, and 25 the upper portion of the body will be covered by the parts functioning as a brassière whereby the mammae of the wearer will be properly supported and yet permit of the free movement of the body desired in dancing and athletic exercises; and whereby a 30 smooth, unbroken outer surface from top to bottom of the garment is maintained, to insure the proper fit of a dress or other garment worn thereover, and any tendency to 35 "ride up" on the body of the wearer is prevented.

To these ends, the invention consists in the devices and combination of devices herein illustrated, described and pointed out in the 40 appended claims.

In that form of the invention illustrated in the accompanying drawings:

Fig. 1 is a front view of a combined corset and brassière constructed in accordance with 45 my invention; and

Fig. 2 is an inside view of the same, opened out.

In the drawing, the back A is composed 50 of seven vertically disposed sections indicated as 1, 2, 3, 4, 5, 6 and 7, all except the central section 4 being of the usual corset material, and secured together along their vertical side margins by stitching, in a familiar manner. The central section 4 may be 55 of similar corset material; but I prefer to

construct it as shown, composed of a plurality of vertical and cross strips, leaving intervening ventilating spaces 8. This ventilated back section is fully disclosed and claimed in my United States Letters Patent, 60 Reissue No. 13,698, of March 10, 1914, and therefore need not be further described.

On the inside of the corset back A, and by means of cloth strips 9, I form pockets, in the upper portions of which, only, I 65 place bones indicated by the dotted lines 10. It will be noted that the bones extend from the top margin of the back A partway over the hips.

The back sections 1 and 2 have an extension 11, at their lower ends adjacent to the strip 9, to which is secured the familiar garter strap 12. A similar extension 13 on the sections 6, 7, carries a garter strap 12.

The corset member as a whole, comprises 75 in addition to a portion of the back, two front extension members B, B, each comprising an adjustable section 14 of elastic or other suitable material, joined along one margin to the sections 1 and 7 of the back, respectively, and a section 15 of corset cloth material joined along one of its margins to the front margin of the section 14. On the inside of one section 15 is a vertical strip 16 containing a plurality of hooks 17 and on the other section 15 is a similar strip 18 provided with eyes 19. When the two extension members B are brought together over the abdominal region, hooks and eyes are 80 engaged and the parts firmly secured together.

Of course, it will be understood that these parts may be secured together by the familiar eyelets and corset lacings, instead of by hooks and eyes. When lacings are used, 85 the elastic sections 14 may be dispensed with, as the necessary adjustment can, in that event, be secured by the lacings. On the inside of each extension member B, and somewhat near its front margin, is a tape 20 forming a vertically disposed pocket for a bone or steel indicated by the dotted lines at 21.

The extension members B, B, are of such 100 length that the upper edges 22 will come approximately to the waist line of the wearer.

The brassière member designated as a 105 whole at C, is secured by stitching at its upper side margins to the upper side mar-

gins of the back sections 1 and 7. As shown, the securing connection between the brassière and the section 7 is by means of hooks 23 on the brassière member and eyes 24 on 5 the section 7. Manifestly, these parts may be secured by sewing, in the usual way, and the brassière centrally opened and provided with hooks and eyes similar to the arrangement shown for the corset extension members 10 B, B. The central, lower portion of the brassière member C is extended downwardly so as to substantially lie over the extension members B, B, and is provided at its lower ends with the usual garter straps 15 25. Shoulder straps D are secured to the back A and to the top margin 26 of the brassière C.

It will be noticed that the brassière member C and the corset member extensions B, B, 20 are so constructed that when the garment is placed upon the wearer, the brassière member must overlie the corset member. To this end it will be noticed that the length of the side margin of the brassière member C is 25 such that said side margin overlies the top side margin of the elastic section 14 of the section B, as indicated at 27. Thus it will be impossible for the user to place the garment upon herself improperly, without dis- 30 torting the same.

It will be seen that by the construction thus described, I have produced a combined corset and brassière, the corset part being provided with such stiffening as is desirable 35 to support the body and yet not interfere with the free movements thereof, while the brassière portion is supported at the top by the shoulder straps and held down at the bottom by the garter straps in such manner 40 as to prevent wrinkling, and preserves the outer surface in a smooth condition so that

outer garments may be properly fitted there- upon.

I claim as my invention:

1. A combination corset and brassière 45 comprising a reinforced corset garment adapted to encircle the wearer's body below the diaphragm and embrace the abdomen and provided with an integral vertically ex- 50 tendsing rear portion adapted to embrace the wearer's back, and a brassière portion per- 55 manently secured to one side of said verti- cally extending rear portion and detach- ably engaging the other and adapted to em- brace the wearer's bosom, said brassière hav- 60 ing a depending portion adapted to overlie the abdomen-embracing portion of the cor- set.

2. A combination corset and brassière comprising a vertically reinforced rear cor- 60 set portion adapted to embrace the wearer's back from arm pit to arm pit at its upper extremity and provided adjacent its lower extremity with forwardly extending reinforced portions adapted to encircle the wear- 65 er's body below the diaphragm and embrace the abdomen interengaging fasteners on said forwardly extending reinforced portions, and a brassière portion permanently secured to one side of said rear portion adjacent said 70 upper extremity and adapted to extend across the wearer's bosom and detachably engage the upper extremity of the rear portion at the opposite side.

In testimony, that I claim the foregoing 75 as my invention I affix my signature, in the presence of two witnesses, this 5th day of February, 1923.

CHARLES H. SCHOPBACH.
